U.S. Cl. D8—34

Fig. 1.

Fig. 2.

Fig. 3.

Fig. 4.

FIG. 1 is a perspective view of a combined can opener and fruit juicer embodying my new design;

FIG. 2 is a top plan view thereof;

FIG. 3 is a side elevational view thereof; and

FIG. 4 is a rear elevational view thereof.

It is understood that the perforations in the juicer bowl, partially omitted from FIG. 2 for convenience of illustration, are continuous about the periphery thereof in the path indicated by the dot-dash lines.

I claim:

The ornamental design for a combined can opener and fruit juicer, as shown and described.
